Design No. 4,939, dated May 23, 1871.

DESIGN FOR CLOCK-FRONT.

The Schedule referred to in these Letters Patent and making part of the same.

To all whom it may concern:

Be it known that I, JOHN H. BELLAMY, of the city of Charlestown, in the county of Middlesex and State of Massachusetts, have originated and designed a new and useful Pattern for a Clock-Front, of which the following is a full, clear, and exact description, reference being had to the accompanying photographs and to the letters of reference marked thereon making a part of this specification.

The nature of my design consists in so arranging emblems as to show above the dial A several balls, B, together with cross-cannons C C, a sword D, the whole being surmounted by an eagle, E.

Below dial A, and on the left of sash L, are a bugle, K, flag I, and cross-swords J J, while on the right of sash L are an anchor, F, flag G, and cross-guns H H; the whole being encircled in ornamental scroll-work, and constituting an ornamental clock-front.

What I claim, and desire to secure by Letters Patent, is—

The design for a clock-front, as shown, described, and set forth.

JOHN H. BELLAMY.
